UNITED STATES PATENT OFFICE.

GEORGE PRIFOLD, OF SOMERVILLE, NEW JERSEY.

IMITATION RAISED TILING.

Application filed September 16, 1926. Serial No. 135,795.

This invention relates to floor covering, and aims to provide an imitation raised tiling which may be manufactured at small cost and laid without difficulty.

5 Imitation tiling made in accordance with the invention consists of a flexible floor covering having a smooth surface, and layers of paint on said surface completely covering and protecting it, and arranged to give the 10 appearance of raised tiles.

In order that the invention may clearly be understood, I will describe in detail a specific imitation tiling embodying the invention, and a specific method of making it.

15 In this description, I shall refer to the accompanying drawings, in which—

Fig. 1 illustrates a strip of imitation tiling during the process of manufacture; and

20 Fig. 2 shows a completed imitation tiling of a different design.

In making imitation tiling in accordance with the invention, I start with a strip of flexible floor covering material, for example, material of the class known as linoleum.

25 This material is passed through a block printing press having blocks supplied with paints of different colors, and adapted to print successively on each short section of the strip as the strip passes through the machine.

30 One of the blocks is supplied with paint which is to serve as the background or field color of the imitation tiling. This block has a printing surface containing one or more open spaces, so that when it is impressed upon the strip, it produces a layer of paint 10, leaving one or more open uncolored spaces 11, as seen at *a* in Fig. 1. One or more figure blocks are provided for printing figures in the open spaces 11. The

40 raised surfaces of these blocks correspond in shape to the open spaces 11, but are of less area. These blocks are supplied with paint of a color different from that used on the field block. The impression of the figure block, on the portion of the strip on which the field block has already been impressed, results in leaving a layer of paint 12 within each of the open spaces 11, as seen at *b* in Fig. 1. The paint figures 12 do not

45 completely fill the open spaces but correspond in shape to the spaces, so that a narrow uncolored portion 13 is left between the outer edge of each figure and the edge of each open space.

50 Two border blocks are provided to fill in the spaces 13 with paint. One of these

blocks is supplied with a light colored paint, preferably white; and the other with a dark colored paint, preferably black. The border blocks are so arranged that one of them 60 places paint in that portion of the border space 13 around each figure which is in a predetermined direction (for example, the direction D in Fig. 1) from the figure, while the other one fills in the remainder of the border spaces, that is, that portion of these spaces which lie in the opposite direction D' from the figures. The result of the impression of the border block provided with white paint is shown at *c* in Fig. 1, from which it 70 will be seen that the portion of the space 13 surrounding each figure which lies in the direction D from the figure has been covered with white paint 14. The result of the subsequent impression of the second border block is shown at *d* in Fig. 1, from which it will be seen that the remainder of the border spaces 13 have been covered with black paint 15.

75 The result of this operation is to cover and protect the entire surface of the material with a layer of paint and, at the same time, to give the figures 12 the appearance of being at a different level from the field 10, thus creating the illusion of raised tiling.

80 The imitation tiling shown in Fig. 2 is of a more complicated design, but is manufactured in the same manner. In this instance, one of the figures 12^a serves as the field for figures 12^b within it, and these figures are 85 provided with borders which are partly black and partly white, so that the figures 12^b appear to be at a different level from the figure 12^a.

90 The shape and arrangement of the figures used is immaterial, so far as the present invention is concerned, and it is apparent that it may be applied to produce imitation raised tiling of any desired design.

95 What I claim is:

100 1. Imitation raised tiling, comprising a flexible floor covering having a smooth surface, a layer of paint on said surface providing a field containing open spaces, a layer of paint of different color forming figures in said spaces conforming to the outline thereof and spaced inwardly from the edges thereof, so as to leave a border space between each figure and the field, a layer of light colored paint filling that portion of the border space 105 surrounding each figure which lies in one direction from the figure, and a layer of dark 110

colored paint filling that portion of the border space surrounding each figure which lies in the opposite direction from the figure, so as to make the figures appear to be at a different level from the field.

2. Imitation raised tiling, comprising a flexible floor covering having a smooth surface, a layer of paint on said surface providing a field, a layer of paint of different 10 color forming figures on the field, a layer of light colored paint forming a border part-

ly surrounding each figure and lying in one direction from the figure, and a layer of dark colored paint forming a border partly surrounding each figure and lying in the 15 opposite direction from the figure, so as to make the figures appear to be at a different level from the field.

In testimony whereof I have hereunto set my hand.

GEORGE PRIFOLD.
